UNITED STATES PATENT OFFICE.

RICHARD M. JUDD, ERNEST C. TAYLOR, AND RALPH S. McNANEY, OF DOWAGIAC, MICHIGAN, ASSIGNORS TO PREMIER WARM AIR COMPANY, OF DOWAGIAC, MICHIGAN, A CORPORATION OF MICHIGAN.

WARM-AIR FURNACE.

Application filed May 23, 1927. Serial No. 193,684.

This invention relates generally to warm air furnaces and consists of certain novel features of construction and combinations and arrangements of parts as more fully 5 hereinafter set forth.

Figure 1 is a side elevation of a warm air furnace with a part of the outer casing broken away;

Figure 2 is a section taken on line 2—2 10 of Figure 1;

Figure 3 is a section taken on line 3—3 of Figure 1.

Referring now to the drawings, the numeral 1 designates the combustion chamber 15 of a warm air furnace, 2 the fuel passage extending laterally therefrom toward the front of the furnace, 3 the radiator positioned above the combustion chamber and 4 the outer casing spaced from and surrounding 20 the combustion chamber. As shown, the radiator 3 is of circular construction having an annular passage 5 and a cross passage 6 communicating therewith at opposite sides thereof and being provided with an opening 25 7 in the bottom wall thereof registering with an opening in the top portion of the combustion chamber.

Heretofore it has been the practice to provide the radiator with an outlet passage 30 for the products of combustion at the rear of the furnace and a clean out passage diametrically opposite the outlet passage at the front of the furnace. It has been found, however, that such an arrangement is undesirable 35 particularly in the molding of the radiator and also after the furnace has been assembled. Such radiators must be made in one piece in order to insure a leak proof casing and where only two points of suspension 40 are provided for the core prints of the mold, it is necessary to provide additional means for supporting the core in the mold.

In the furnace constructions now in use the arrangement is such that it is usually impractical to provide a warm air riser extending directly from the front of the furnace because of the fact that the clean out pipe would be positioned directly below the point where the front riser would be placed 50 and thereby block the passage of warm air ascending to the riser. However, such an arrangement is often desirable in order to obtain the most efficient heating arrangement and the inability to so position a riser

at this point has necessitated the placing of 55 the same off to the side of the furnace at an angle to the front thereof.

In the present invention these objectionable features have been eliminated by providing the radiator with a pair of spaced 60 clean out pipes 9 and 10 diverging outwardly from the annular passage 5 upon both sides of the front of the furnace, the outlet 8 being located at the rear of the radiator in the usual manner. 65

By such a construction it will be readily apparent that the molding operation of the radiator is much simplified, as three points of suspension are now provided, thus eliminating the necessity of providing additional 70 means for holding the core prints in correct position.

It will also be apparent that when applicants' radiator is assembled with the rest of the furnace, the arrangement will be such 75 that each clean out pipe will be positioned directly above and to the side of the fuel supply passage so that the warm air rising between the combustion chamber and the outer casing 4 will be deflected upwardly in 80 two streams between the fuel supply passage and each pipe. As shown by the arrows in Figures 2 and 3 these streams will merge into a single stream and continue to rise between the front wall 11 and the front of the 85 radiator, finally entering the riser 12.

It should be stated that each pipe is provided at its outer end portion with a door 13 normally in closed position. Pivottally mounted in the cross passage 6 is a direct 90 draft regulator 14, which is adapted to be operated upon the opening or closing of the fuel door by any suitable mechanism (not shown) for regulating the flow of the products of combustion through the radiator. 95

From the foregoing, it will be apparent that we have provided an improved form of radiator for warm air furnaces which greatly facilitates the molding operation thereof and which when assembled with the remainder of the furnace parts provides for the advantageous positioning of a front riser and assists in directing a sufficient quantity of warm air to the riser. 100

What we claim as our invention is:—

In a warm air furnace, the combination with a combustion chamber having a lateral fuel passage extending toward the front of

the furnace, of a radiator having an annular channel connecting with said combustion chamber and provided with a pair of spaced clean out passages extended laterally therefrom above said fuel passage at each side thereof in close proximity thereto, a front furnace wall having its upper portion extending between said clean out passages and spaced from the front portion of said radiator, an outer casing surrounding said combustion chamber and forming therewith an

air passage and a riser extending directly from the front of the furnace between said clean out passages, the arrangement being such that warm air rising within the outer casing will be directed between the fuel and clean out passages into said riser. 15

In testimony whereof we affix our signatures.

RICHARD M. JUDD.
ERNEST C. TAYLOR.
RALPH S. McNANEY.
